UNITED STATES PATENT OFFICE

155,281

DESIGN FOR AN AMPHIBIAN AIRPLANE

Athanas P. Fontaine, Detroit, Mich., assignor to
 Béndix Aviation Corporation, Detroit, Mich., a
 corporation of Delaware

Application June 21, 1946, Serial No. 130,926

Term of patent 7 years

(Cl. D71—1)

To all whom it may concern:

Be it known that I, Athanas P. Fontaine, a citizen of the United States, residing at Detroit, in the county of Wayne and State of Michigan, have invented a new, original, and ornamental Design for an Amphibian Airplane, of which the following is a specification, reference being had to the accompanying drawings, forming a part thereof.

Fig. 1 is a top plan view of an amphibian airplane;

Fig. 2 is a front elevation;

Fig. 3 is a side elevation; and

Figure 4 is a perspective view of the rear end of the amphibian airplane.

The characteristic features of my design reside in the portions shown by means of full lines in the drawing wherein the fuselage is depicted as having a beaver-tail extension at the rear end thereof.

I claim:

The ornamental design for an amphibian airplane, as shown and described.

ATHANAS P. FONTAINE.
